SOLE FITTING MACHINE

Joseph C. Cantley, Beverly, Mass., assignor to
United Shoe Machinery Corporation, Flemington, N. J., a corporation of New Jersey

Application November 13, 1941, Serial No. 418,959

4 Claims. (Cl. 12—17)

This invention relates to sole fitting machines, and is herein illustrated as embodied in a feather edge and shank reducing machine. Machines of this type are provided with a stationary knife for making an inclined or skiving cut upon the flesh surface of a sole as the sole is being fed past the knife in contact with an edge gage. The knife is mounted for adjustment of the inclination of its cutting edge to enable the angle of the cut to be varied.

In accordance with a feature of the present invention, the illustrated machine is provided with a knife support rotatably mounted in a bearing to enable the inclination of the knife to be varied, this knife support having an arm extending to a locality convenient to the operator to facilitate making the adjustment. The machine is further provided with a carrier upon which both the knife and the edge gage are mounted, the carrier being movable for adjustment in a direction transverse to the feed of the sole. In the illustrated machine, not only the knife and the edge gage are mounted upon this carrier but a work support is also mounted upon it to enable these members to be adjusted simultaneously in a direction transverse to the feed of the work without disturbing their relation to one another.

These and other features of the invention, including certain details of construction and combinations of parts will be described as embodied in an illustrative machine and pointed out in the appended claims. Referring now to the accompanying drawings,

Fig. 1 is a view partly in end elevation and partly in section of the head of a machine in which the invention is embodied;

Fig. 2 is a view in side elevation of the head of the machine shown in Fig. 1;

Fig. 3 is a section on the line III—III of Fig. 1;
Fig. 4 is a section on the line IV—IV of Fig. 2; and

Fig. 5 is an angular view of the knife carrier and associated parts.

The operating instrumentalities of the machine consist of a shank reducing or feather edging knife 10 (Figs. 3, 4 and 5), a work support 12, a feed wheel 14 (Figs. 2 and 3), a presser foot 16 (Fig. 2), and an edge gage 18 (Figs. 2 and 4). The supporting structure of the machine comprises a standard 20 upon which is mounted a head 22.

The knife 10, the work support 12, and the edge gage 18 are all indirectly carried by a block 24 which is slidably mounted for horizontal ad-

justment in a direction transverse to the feed of the work. The head 22 is provided with a horizontal guideway for the block 24, and a winged clamping bolt 26, extending through a horizontal slot 28 in the block and threaded into the head 22, clamps the block in adjusted position. The work support 12 is in the form of a driven rotary table of frusto-conical form, the vertex angle of the cone being obtuse. This table is carried upon the upper end of a shaft 30 journaled in bearings carried in a bracket 32 secured by screws 33 (Fig. 2) to the block 24. A tongue and groove connection 35 (Fig. 1) between the bracket 32 and the block 24 permits adjustment of the block relatively to the bracket in a direction which is horizontal and transverse to the direction of feed of the work. The screws 33 are threaded into the block 24 and pass through suitable slots in the bracket 32. The purpose of the adjustment is to secure proper meshing of the gears, later to be described, which drive the work table. The axis of the shaft 30 is inclined from the vertical at such an angle as to cause the work-engaging elements of the frusto-conical surface to be substantially horizontal. The only movement of the work support 12 relative to the block 24, except the adjustment provided by the tongue-and-groove connection 35, is one of rotation about the axis of the shaft 30.

The knife 10, as shown in Figs. 4 and 5, is clamped in a block 34 having a guideway substantially parallel to the blade of the knife. The shank of the knife is clamped in this guideway in any desired position of longitudinal adjustment by a clamping bolt 36 passing through a clamping block 38 and threaded into the block 34. A plate 40, adjustably mounted upon the block 34, has a shouldered portion 42 engageable with the end of the shank of the knife to facilitate reinsertion of the knife, after sharpening, to a predetermined position of adjustment. The block 34 is integral with an arcuate slide 44, which is rotatable in an arcuate guideway 45 formed in a supporting bracket 46. The bracket 46, as illustrated, is recessed at the locality indicated by the reference numeral 47 to provide a clearance space through which the sole may pass as it is being fed at various angles determined by its edge contour. The slide 44 has a cylindrical edge face 48 which directly engages the complementally curved surface of the guideway 45, and it has also an outer edge face 50 which is conical or beveled for engagement with a complementally shaped surface formed on a clamp-

ing block 52. The clamping pressure of the block 52 is obtained by a bolt 54 passing through the block 52 and threaded into the bracket 46. Angular adjustment of the slide 44 may thus be effected by loosening the bolt 54, turning the slide to the desired adjusted position, and then tightening the bolt 54. Extending upwardly from the bracket 46 is a plate 56 the upper end portion of which, as shown in Fig. 3, is in the form of a graduated sector 58 concentric with the axis of the guideway 45. Extending upwardly from the slide 44 is a pointer 60 which cooperates with the sector 58 to indicate the adjusted position of the knife. The pointer is longer than the distance of the knife from the center of rotation of the slide 44, and it will therefore be readily seen that by means of the pointer 60 and the sector 58 the operator may effect a fine adjustment of the knife. Both the pointer 60 and the sector 58 are positioned conveniently for observation and access, and at a locality remote from the knife to permit a clear view of the operation.

Formed on the under surface of the bracket 46 is a tongue 62 (Figs. 3 and 5) which is slidable in a horizontal guideway formed in a block 64. The purpose of this slidable connection is to provide for adjustment of the knife in a direction parallel to the feed of the work and transverse to the direction to which the block 24 may be adjusted. When the blade of the knife 10 is ground away in sharpening, the adjustment afforded by this tongue and groove enables the new cutting edge of the knife to be brought into proper operating position. The block 46 may be secured in any desired position of adjustment along the guideway by a clamping bolt 66 (Fig. 1) extending upwardly through a slot 67 (Fig. 4) in the block 64 and threaded into the bracket 46. The block 64 is slidably mounted in a vertical guideway formed in a downward extension 68 of the block 24. An open side of this vertical guideway is closed by a retaining plate 69 and the lower end of the guideway is closed by a cover plate 70. Threaded into the lower end of the block 64 is a screw 72 upon which is rigidly mounted a collar 74 (Fig. 1). A compression spring 76, housed within a bore formed in the block 64, urges the block downwardly to a stop position determined by engagement of the collar 74 with the upper or inner surface of the cover plate 70. This stop position may be varied for purposes of adjustment by turning a hand wheel 78 secured upon the lower end of the screw 72. The upper end of the spring 76 abuts against a transverse pin 80, which is anchored in the block 24 and which extends through a vertical slot 82 (Fig. 3) formed in the block 64 to accommodate heightwise movement of the block 64. The lower end of the spring 76 abuts against a plug 86 threaded into the lower end of the bore which contains the spring. Turning of the plug 86 serves to adjust the degree of compression of the spring. It will be observed that the above-described arrangements for mounting the knife 10 enable the knife to be adjusted vertically, horizontally in a direction parallel to the feed of the work, and also angularly about the axis of the arcuate guideway 45. This axis is horizontal, extending parallel to the direction of feed of the work, and lying in a vertical plane which is tangent to the edge of the work table 12 and to the work-engaging portion of the edge gage 48. As the knife is adjusted vertically, the axis about which it is adjusted moves up and down with it. In addition to the adjustments just described, it will be noted that

the position of the knife and of the axis about which it may be adjusted depend also upon the horizontal adjustment of the block 24 in its guideway.

5 The edge gage 48 is tangent to the work table, allowing for reasonable clearance, at a point directly below the axis mentioned in the preceding paragraph and it extends almost to the cutting edge of the knife. The edge gage is secured by a clamping bolt 87 to an arm 88 (Figs. 1 and 2) fulcrumed upon a pin 90 carried by the block 24. The clamping bolt passes through an opening in the edge gage large enough for the slight degree of shop adjustment which may be necessary. 10 The arm 88 is free to swing up and down in a suitable slot formed in the block 24. A compression spring 92, housed in a bore within the block 24, engages the under surface of the arm 88 to urge the edge gage upwardly against an extension 15 89 of the presser foot 16. The presser foot thus controls the heightwise position of the edge gage, and the edge gage rises and falls in accordance with the varying thickness of the work piece. An ordinary presser foot, without the extension 89, may be used if desired. In such case, the 20 arm 88 is secured in a suitable position of heightwise adjustment by a screw 91 threaded into the block 24 and having its end engageable with a side of the arm 88 to clamp the arm against a 25 wall of the above-mentioned slot.

30 The feed wheel 14 is carried upon the outer end of a shaft 94 which is journaled in a head 96 which extends over the knife 10. A guard 97 carried by the head 96 partly encloses the feed wheel. Extending from the head 96 in a direction 35 parallel to the feed of the work is an arm 98 (Fig. 1), which is fulcrumed upon a pin 100 mounted in a bracket 102 extending from the head of the machine 22. The arm 98 and the head 96, together with the feed wheel 14, are thus 40 vertically movable about the pin 100 and the feed wheel may, therefore, yield heightwise to accommodate variations in the thickness of a work piece. As shown in Fig. 2, the movable head 96 has a finished surface slidably engageable for 45 additional support with a finished surface 103 on the machine head 22. In order to hold the feed wheel 14 down against the work piece upon which it is operating, there is provided a lever 104 fulcrumed upon a pin 106 secured in the head 22 of the machine. Bearing downwardly upon the lever 104 is the lower end of a compression spring 108, the upper end of which spring bears against 50 a knurled head 110 of a screw 112 threaded into the head 22. Interposed between the outer end of the lever 104 and the head 96 is a strut 114 having rounded ends engageable with complementally formed recesses in the lever and in the head. The compression of the spring 108 and 55 accordingly the degree of pressure of the feed wheel against the work may be varied by turning the nut 110. In order to limit downward movement of the feed wheel and prevent its engagement with the work table 12, there is provided a 60 stop screw 116 (Fig. 1) threaded through an extension 118 carried by the swinging arm 98, the lower end of the screw 116 being engageable with a surface formed on the machine head 22.

65 The presser foot 16 is positioned immediately in advance of the cutting edge of the knife 10 in order to hold the sole firmly upon the work table. The presser foot is carried upon the lower end of a slide 120 (Fig. 2) which is vertically slidable in a guideway formed in the head 96. A cover plate 121 retains the slide 120 within the guide-

way. The presser foot has a tongue-and-groove connection 123 (Fig. 2) with the slide 120 to provide for adjustment of the presser foot in the direction of feed of the work. A clamping bolt 125 passing through a suitable slot in the slide 120 secures the presser foot to the slide in any adjusted position. A compression spring 122 surrounding a pin 124 urges the slide 120 downwardly to cause the presser foot to bear upon the work. The pin 124 is secured in and extends upwardly from the slide 120. The upper end of the spring 122 bears against a nut 126 loosely surrounding the pin 124 and threaded for heightwise adjustment into a bracket 127 carried by the head 96. The spring 122 is weaker than the spring 108 and stronger than the spring 92. Its force may be varied to vary the pressure of the presser foot on the work by turning the nut 126. A nut 128 backed up by a lock nut 129 and threaded upon the upper portion of the pin 124 engages the bracket 127 to prevent the presser foot from striking the work table when there is no work piece on the work table.

In order to provide for raising the feed wheel and the presser foot to facilitate the insertion of a work piece, a lever 130 (Figs. 1 and 2) is fulcrumed upon a pin 132 carried by a boss 133 on the bracket 102 (Fig. 1). Extending downwardly from one end of the lever 130 is a rod 134 secured at its lower end to a treadle (not shown). The other end of the lever 130 is connected to a link 136 which transmits movement of the lever to the arm 98. It is evident that depression of the treadle above-mentioned will operate through the lever 130 and link 136 to raise the feed wheel 14 and presser foot 16 against the force of the spring 108. The connection between the lever 130 and the link 136 includes a knurled nut 135 and a winged locknut 137 both threaded upon the upper end portion of the link 136. The link 136 passes loosely through an opening in the lever 130, and the lever bears upwardly against the nut 135 when the treadle is depressed. The nut 135 may be adjusted upwardly to provide lost motion for a purpose later to be explained.

It is desirable also to provide for raising the knife 10 when a new work piece is to be inserted. This is accomplished by a lever 138 fulcrumed upon a pin 140 (Figs. 3 and 4) mounted in the head 22 and engageable at one end with a collar 142 (Fig. 1) adjustably mounted upon the rod 134. The opposite end of the lever 138 bears upwardly against an under surface of the block 64. Depression of the treadle will, therefore, raise the block 64 against the compression of the spring 76.

The purpose of the above-mentioned provision for lost motion between the lever 130 and the link 136 is to enable the knife to be raised without raising the feed wheel and the presser foot. When the machine is thus adjusted for lost motion, a sole may be fed entirely around, with its edge portion constantly engaged by the feed wheel and the presser foot, while the knife may be raised by a partial depression of the treadle to avoid acting upon the heel portion of the sole.

The feed wheel 14 and the work table 12 are both positively driven from a shaft 144 (Fig. 3) journaled in the machine head 22 and carrying at its outer end a pulley 146 (Fig. 1) which may be connected by a belt to any suitable source of power. Secured upon the shaft 144 is a gear 148 which transmits rotation through an idler gear 150 to a gear 152 secured upon the end of a shaft 154 journaled in the block 24. The opposite end

of the shaft 154 carries a beveled gear 156 which drives a beveled gear 158 carried by the shaft 30 directly under the work table 12. Meshing with the gear 152 and driven thereby is a gear 160 journaled upon a ball bearing 162 secured in a plate 163 mounted on the head 22. Extending from the gear 160 is a short shaft 164 which is connected, through an intermediate shaft 166 and two universal joints 168, to the shaft 94. Drive of the feed wheel may thus be effected from the gear 160, notwithstanding the heightwise movement of the feed wheel.

In the operation of the machine, the feed wheel, the presser foot and the knife are all raised by the operation of the treadle above-mentioned. A sole S is then presented upon the work plate 12 with the edge face of the sole against the edge gage 18. Upon release of the treadle, the feeding movement of the sole begins. The angle of the beveled cut made in shank reducing or the angle of the feather, if the operation is around the forepart of the shoe, may be varied by the angular adjustment of the knife slide 44 about the axis of the guideway 45. It will be observed that the point to which the knife intersects the edge face of the sole will not be varied by this angular adjustment because the center about which the knife rotates is in the edge face of the sole itself. This adjustment may be made accurately by reason of the long pointer 60 and the graduated sector 58, and it may be made easily because both the pointer and the sector are positioned above the feed wheel in a locality conveniently accessible to the operator. Heightwise adjustment of the knife will of course not affect its angular adjustment. It will also be noted that horizontal adjustment of the block 24 in a direction transverse to the feed of the work will serve to adjust the work table, the knife, and the edge gage in unison relatively to the feed wheel and to the presser foot, without disturbing the relations of the work table, the knife, and the edge gage to one another. Such provision for horizontal adjustment enables the operator to keep the distance between the upper feed wheel and the end of the knife down to a minimum. Knives of different length are provided according to the particular kind of work to be done and therefore in the case of a short knife the upper feed wheel will be closer to the edge gage, and in the case of a long knife the upper feed wheel will be farther from the edge gage. The arrangement disclosed herein for horizontal adjustment is more convenient in operation and more economical in manufacture than any provision for adjusting the feed wheel itself axially.

Having thus described my invention, what I claim as new and desire to secure by Letters Patent of the United States is:

60 1. A sole fitting machine, comprising a work table, a knife for beveling the margin of a sole on said work table, a feed wheel engageable with the sole beyond the end of said knife, a head extending over said knife for supporting said feed wheel, an arcuate guideway, a slide carrying said knife and slidable in said arcuate guideway to enable the inclination of the knife to be varied, an arm extending upwardly from said slide and to one side of said head to a height greater than the height of the head and of the feed wheel, said arm being conveniently accessible to the operator to facilitate movement of the slide in the guideway to a desired position of adjustment of the knife, and a graduated sector adjacent to and 65 cooperating with said arm to enable the operator 70 to adjust the angle of the knife. 75

to determine said position of adjustment, said arm being longer than the distance of said knife from the center of the arcuate guideway for purposes of fine adjustment.

2. A sole fitting machine, comprising sole feeding means, a knife for operating upon a sole, an arcuate guideway, a slide carrying said knife and slidable for adjustment in said arcuate guideway to vary the inclination of the cutting edge of the knife relatively to the sole, an edge gage, and a common carrier for said arcuate guideway and said edge gage, said carrier being adjustable relatively to the feeding means in a direction transverse to the feed of the sole, and said arcuate guideway being positioned in said carrier to cause the axis about which the inclination of the knife may be varied to lie in a plane tangent to the work-engaging portion of the edge gage, said relation between the arcuate guideway and the edge gage remaining constant notwithstanding transverse adjustment of the carrier. 20

3. In a sole fitting machine, a work table, a tool for operating upon a sole on said work table, an edge gage for gaging the sole relatively to said

tool, a common carrier for said work table, said tool and said edge gage, said common carrier being adjustable to move the work table, the tool and the edge gage in unison in a direction transverse to the feed of the work, means for yieldably holding said tool down in a normal position for operation, and operator-controlled means for raising said tool relatively to said work table. 5

4. In a sole fitting machine, a work table, a tool for operating upon a sole on said work table, an edge gage for gaging the sole relatively to said tool, a common carrier for said work table, said tool and said edge gage, said common carrier being adjustable to move the work table, the tool and the edge gage in unison in a direction transverse to the feed of the work, a slide for carrying said tool, said common carrier having a guideway in which said tool-carrying slide may be adjusted in the direction of feed of the work independently of the work table, and means for securing said slide in a fixed position of adjustment in said guideway. 10 15

JOSEPH C. CANTLEY.
